MAGNETIC ACTUATOR

Osborne L Price, Frederick, Md., assignor to Magnetic Devices, Inc., Frederick, Md., a corporation of Maryland

Application October 23, 1941, Serial No. 416,268

12 Claims. (Cl. 175—336)

My invention relates broadly to magnetic actuators and more particularly to a magnetic actuator having a high degree of turning torque for relatively low applied actuating current.

This application is a continuation-in-part of my application Serial No. 392,166, filed May 6, 1941, for Magnetic actuator.

One of the objects of my invention is to provide a construction of magnetic actuator which may be inexpensively manufactured on a quantity production basis and which may be depended upon to produce high turning torque under control of relatively low actuating current.

Still another object of my invention is to provide a construction of magnetic actuator of small compact size having high electrical efficiency and which develops relatively high turning torque under control of relatively low applied operating current while substantially eliminating development of end thrust on the rotatable armature.

A further object of my invention is to provide a construction of magnetic actuator having means for centering a rotatable armature for rotary movement within a magnetic winding with magnetic operating faces formed adjacent opposite ends of the rotary armature arranged to coat with magnetic faces of the magnetic actuator for effecting rotary movement of the armature without developing end thrust forces.

A still further object of my invention is to provide a construction of magnetic actuator which includes a rotatable armature having pairs of magnetic operating faces adjacent opposite ends thereof which are formed on contours which are cam-shaped and which coat with cam-shaped faces in magnetic plates supported at opposite ends of the magnetic actuator whereby a high turning torque may be produced under control of relatively low applied actuating current.

Another object of my invention is to provide an arrangement of magnetic plate members for opposite ends of a magnetic actuator employing an electromagnetic operating winding and a rotatable armature journaled with respect thereto in which the rotatable armature is provided with pairs of magnetically cam-shaped faces adjacent opposite ends of the armature coacting with magnetically cam-shaped internal faces on the magnetic plates adjacent opposite ends of the actuator and in which non-magnetic inserts are arranged having limiting abutments thereon for controlling the angular movement of the actuator.

Still another object of my invention is to provide a construction of magnetic actuator includ-

ing a field magnet and a rotatable armature wherein the rotatable armature is provided with pairs of faces thereon coacting with pole pieces forming part of the magnetic actuator where the faces and pole pieces are so formed as to continuously reduce the magnetic reluctance of the magnetic path as the device is actuated, thereby causing rotation of the armature.

Other and further objects of my invention reside in the construction of rotatable armature and arrangement of actuating magnetic pole pieces therefor as set forth more fully in the specification hereinafter following by reference to the accompanying drawings, in which:

15 Figure 1 is a side elevational view of the magnetic actuator of my invention; Fig. 2 is a top plan view of the magnetic actuator embodying my invention; Fig. 3 is a horizontal sectional view taken on line 3—3 of Fig. 1; Fig. 4 is a horizontal 20 sectional view taken on line 4—4 of Fig. 1; Fig. 5 is a transverse sectional view through the magnetic actuator taken on line 5—5 of Fig. 2, the armature being illustrated in side elevation; Fig. 6 is a perspective view of one of the laminations 25 constituting the magnetic plates forming the pole faces adjacent opposite ends of the armature; Fig. 7 is a perspective view of the magnetic armature; Fig. 8 is a plan view of a typical magnetic plate showing the arrangement of pole faces thereon 30 and illustrating the relationship of the movable armature and the spiral faces thereof with respect to the operating faces of the magnetic plate and showing the arrangement of the non-magnetic inserts in the magnetic plate; Fig. 9 is a schematic view of the electrical circuit through the operating winding of the magnetic actuator; and Fig. 10 shows a modified form of magnetic actuator embodying my invention in which an operating member extends from each end of the device, thereby facilitating the mounting of the device in any selected position.

My invention is directed to a construction of magnetic actuator wherein all available forces are utilized for effecting rotary movement of the armature. There are no appreciable thrust forces. The magnetic actuator of my invention is the result of extended investigation, research and development. In experimenting with various constructions of magnetic devices, I discovered that with a magnetic actuating member on one end only of the armature the thrust encountered in the neutral position (that is, a position of the armature where it would neither move clockwise nor counterclockwise) the energy necessary to overcome the end thrust of the armature

was as much as $4\frac{1}{2}$ " ounces. The gap necessary at one end of the armature while serving no useful purpose in developing turning torque did contribute to the development of end thrust forces. I then developed the rotatable armature by applying a magnetic actuator adjacent each end of the device. Even though this apparently introduced additional air gap, the turning torque obtained, due largely to the substantially complete elimination of end thrust, was noted to be more than twice the usual turning torque obtained with a single ended device. Pairs of faces are carried by the armature adjacent opposite ends thereof. The magnetic plate members through which the faces of the armature extend are shaped to coact with the faces on the armature. The external faces on the armature and the internal faces on the plate members are so formed as to continuously reduce the magnetic reluctance of the magnetic path through the armature as the armature is angularly shifted. That is to say, the coacting faces are so formed that they coact to continuously reduce the magnetic reluctance of the magnetic path therethrough so as to produce rotary movement. The faces of the armature are composite in contour including radially extending faces and curved faces that coact with faces on the plate members to reduce the magnetic reluctance of the magnetic circuit to produce rotary motion.

Referring to the drawings in detail, reference characters 1, 2 and 3 designate laminated magnetic plate stampings which are stacked upon each other to form one of the pole pieces of the magnetic actuator. Reference characters 4, 5 and 6 represent similar magnetic plate stampings which are stacked to form the opposite end of the magnetic actuator. A pair of magnetic end frame members 7 and 8 are arranged between the sets of stacked plates. The plates are normally aligned with respect to the end frame members 7 and 8 by means of dowel pins indicated generally at 9 and 10 in Figs. 2 and 3 which project through aligned apertures as represented, for example, at 1a and 1b in the plate member illustrated in Figs. 6 and 8 in the end plates and into the end frame members 7 and 8. To insure the precision assembly of the magnetic actuator and to provide bearings for the angular movement of the rotary member, I provide stamped end plates of non-magnetic material represented at 11 and 12. These end plates are preferably formed of phosphor bronze and are each provided with skirted edge portions at opposite ends adapted to extend over at least one thickness of the stacked magnetic plates and form a confining and positioning means therefor and serve to align the laminations. For example, end plate 11 has a skirt 11a extending from the peripheral edge at one end thereof and the skirt 11b extending from the opposite edge thereof. End plate 12 has skirt 12a extending from one end thereof and skirt 12b extending from the opposite end thereof. Sets of headed screws 14 extend through plate 11 and through the aligned apertures indicated, for example, at 1c and 1d in the magnetic plates 1, 2 and 3, and into screw threaded apertures indicated at 15 in the magnetic end frame members 7 and 8. End plate 11 is provided with a circular outstruck projection 16 from which the inwardly directed annular sleeve bearing portion 17 extends. The end plate 12 has a similar outstruck circular portion 18 with which there is integrally formed the inwardly extending annular sleeve bearing portion 19. A mounting plate

20 is provided for supporting the magnetic actuator. The mounting plate 20 is centrally apertured at 21 for receiving the outstruck circular portion 18 of the end plate 12. The mounting plate 20 is apertured at 22 for the passage of the flat headed screws 23 which extend through aligned apertures in the stacked plates 4, 5 and 6 and into the magnetic end frame members 7 and 8 as indicated at 24. The mounting plate 20 may be secured in any desired position by means of lug 25 and the apertures 26 in the mounting plate.

The actuating winding for the magnetic actuator is formed by a pair of windings 27 and 28 schematically shown in Fig. 9 and illustrated in Figs. 1, 4, 5 and 10 as wound upon the coil support form 29. To facilitate maintaining the position of the windings, I provide circular end plate centering members 30 and 31, which include inturned annular sleeve-like end portions 30a and 31a which extend toward each other and provide bearings for the angularly shiftable armature indicated generally at 32. The end plate centering members 30 and 31 are each formed from non-magnetic material such as brass and serve as supporting means for the coil form 28 and windings 27 and 28 thereon.

The windings are so connected that current is normally supplied to winding 27 from current supply circuit indicated at 33, the current passing through contactor 34 which is initially closed. The current in the starting winding 27 energizes this winding and angularly shifts armature 32 which carries switching means including the contactor 34 which when opened causes the excitation of winding 28 which is a high resistance holding winding. Windings 27 and 28 thus coact to impart angular movement to armature 32 and to hold armature 32 in its shifted position.

The angularly shiftable armature or rotor 32 is shown more clearly in perspective view in Fig. 7 from which it will be observed that sets of cam-shaped faces 35 and 36 are provided adjacent opposite ends of the rotor. Each set of cam-shaped faces is composite in contour and includes radially extending faces 35a and 35b and face 35f for the set of cam-shaped faces 35 and corresponding radially extending faces 36a and 36b and face 36f for the cam-shaped faces 36 of the armature, as shown in Fig. 5. The radially extending faces are connected at their outer extremities with the curved cam-shaped faces which I have indicated, for example, in Fig. 8 as 35c and 35d. The curved cam-shaped faces terminate in chordal faces 35e and 35f which connect with parallel extending faces 35g and 35h respectively. Both ends of the angularly shiftable armature are symmetrically constructed and the shaped pole faces as explained coact with the sets of pole faces formed by the magnetic laminations constituted by magnetic plates 1, 2, 3, and 4, 5, 6.

These stacks of magnetic plates are apertured to permit the passage of the shaped magnetic faces at each end of the armature. The magnetic plates have correspondingly shaped apertures which provide pole faces coacting with the magnetic faces on the angularly shiftable armature. Each of the magnetic plates includes curved portions which I have represented at 37 and 38 and angularly extending portions 39 and 40. The angularly extending portions 39 and 40 are parallel to each other and are substantially chordal with respect to the cylindrical body portion of the armature 32. The laminated plates are cut out on opposite sides of the center thereof along

angular lines indicated at 41 and 42 and within these cut out portions I provide non-magnetic inserts formed from any suitable material such as brass and indicated at 43 and 44. These non-magnetic inserts 43 and 44 constitute limiting stops for the angular movement of the armature. That is to say, the non-magnetic insert 43 has a face 43a extending in a plane substantially parallel to diametrical lines through the actuator, with a face 43b extending substantially parallel to the transverse axis of the magnetic plate interconnected by a face 43c which is off-set from the face 39 but which extends in a plane parallel thereto. The non-magnetic insert 44 has a correspondingly arranged set of faces, that is, a face 44a substantially parallel with the face 43a, a face 44b substantially parallel to the face 43b, and the face 44c substantially parallel to the face 43c. In each instance these faces of the non-magnetic inserts coact with the cam-shaped faces of the rotor. That is to say, the non-magnetic faces 43b and 44b constitute abutments for magnetic faces 35a and 35b of the set of cam shaped faces 35, whereas magnetic faces 39 and 40 coact with magnetic faces 35f and 35e in effecting rotary movement of the armature in cooperation with the magnetic coaction which extends between the curved faces 35c and 35d with respect to curved faces 37 and 38. The external faces 35c and 35d on the armature are so shaped with respect to the internal faces 37 and 38 on the magnetic plate members that the magnetic reluctance of the magnetic path through the armature is continuously reduced as the armature is angularly shifted.

A wire-like spring member 45 is looped around the armature and is fastened at the end 45a thereof in a socket formed in the end of the armature 32 and is fastened at the opposite end at 45b in a socket formed in one of the end plates represented at 1. The wire-like spring member is housed for operation beneath the circular out-struck projection 16 of end plate 11. The spring tends to yieldably bias the armature to a position in which the magnetic faces 35e and 35f on the armature have maximum magnetic separation from magnetic faces 40 and 39 on the magnetic end plate whereby magnetic excitation of the actuating winding 27-28 effects rotary movement of the armature.

The armature 32 has extensions 46 and 47 on opposite ends thereof which project into the annular sleeve bearing portions 17 and 18 of the end plates 11 and 12, whereby the rotary armature is journalled for angular movement. Either of the extensions 46 and 47, or both of said extensions, may be further extended to provide actuating means for any desired load to be operated by the magnetic actuator as, for example, a switch, circuit controller or any other device. One end of the extension of the armature such as the end 47 is suitably shaped to provide a key-way connection with the load to be actuated such as, for example, through the flattened surfaces 47a illustrated in Figs. 1-3 and Figs. 5 and 7. If it is desired to operate a load from the opposite end of the magnetic actuator, the end 46 may be further extended as represented at 46a in Fig. 10 and provided with flattened surfaces 46b for effecting a connection with the load.

In illustrating my invention, I have shown one set of representative proportions for a magnetic actuator embodying my invention. The angular relationships selected have proven very effective in practice and the proportions shown have been found particularly efficient but it is realized that

changes in these proportions and angular relationships may be made and that there are no limitations intended by the illustrative proportions given in Fig. 8. The magnetic plate and the armature have been shown in enlarged view in order to properly illustrate the essential details thereof. It will be understood that the cylindrical portion 32 of the armature has the end portions thereof adequately clearing the stacked end plates 1, 2, 3, and 4, 5, 6, so that the armature may angularly shift with respect thereto.

It will be understood that the magnetic frame of the magnetic actuator while shown closely conforming with the shape of the actuating windings 27-28 may have other configurations although the shape shown has been found to be particularly effective. The important feature and aspect of my invention is the shaping of the magnetic faces of the rotor and the magnetic faces of the coacting end plates for the reduction of magnetic reluctance in producing angular movement. The rotor can be made in a variety of different shapes which will produce the same result and does not necessarily have to be "cam" shaped as applied in mechanics. The rotor may have numerous shapes which will produce cam action "magnetically" and will not be strictly "cam" shaped as thought of generally in mechanics. The surfaces of the magnetic faces may be so designed that they will produce the effect of cams, or will reduce "magnetic reluctance" and yet may not have the appearance of cams.

While I have described my invention in certain preferred embodiments, I desire that it be understood that modifications may be made and that no limitations upon my invention are intended other than may be imposed by the scope of the appended claims.

What I claim as new and desire to secure by Letters Patent of the United States is as follows:

1. A magnetic actuator comprising in combination a magnetic frame, an electromagnetic actuating winding disposed within said frame and having an axial bore extending therethrough, an angularly shiftable armature member journaled with respect to each end of said magnetic frame and having a centrally disposed magnetic portion located within said electromagnetic actuating winding and having pairs of symmetrically arranged magnetic pole faces adjacent each end thereof extending continuously from a radial position to a curved surface and connecting with a plane surface displaced from the axis of the armature and extending to a tangential surface connected with the armature, said pole faces being magnetically associated with each end of said magnetic frame, said armature member operating to continuously reduce the reluctance of the magnetic path between said pole faces and said magnetic frame while increasing the power derived from angular motion, and motion transmitting means connected with said armature member.

2. A magnetic actuator comprising in combination a closed magnetic frame having magnetic end plates at each end thereof, sets of pole faces formed in said magnetic end plates, an electromagnetic actuating winding disposed within said frame and having a bore therethrough aligned with the sets of pole faces in said magnetic end plates, an angularly shiftable magnetic armature having cylindrical extensions on opposite ends thereof, non-magnetic end plate members secured to said magnetic end plates and providing bearings for said extensions, pairs of composite mag-

netic pole faces extending continuously from a radial position adjacent the cylindrical extensions through a curved surface to a plane surface displaced from the axis of the armature and connected with a plane surface extending tangential to the cylindrical extensions adjacent opposite ends of said armature in alignment with the sets of pole faces formed in each of said magnetic end plates, a central magnetic portion of said armature located within said actuating winding, said magnetic armature operating to continuously reduce the reluctance of the magnetic path between said pole faces and said magnetic end plates while increasing the power derived from angular motion, and means on one of said cylindrical extensions for attaching a device to be angularly shifted by said magnetic actuator.

3. A magnetic actuator of compact size having an electromagnetic field structure, a field winding associated with said field structure, a rotatable armature, journals extending from each end of said armature for mounting said armature for angular movement within said field structure, said armature having extended ends carrying pole faces which are respectively curved, radial, tangential and displaced in parallel extending chordal positions on opposite sides of the armature relative to said journals which coact with the field structure in such manner as to continuously reduce the reluctance of the magnetic circuit causing rotation of the armature through a predetermined limit of travel when the field winding is energized.

4. A magnetic actuator of compact size comprising an electromagnetic field structure, field pieces for said structure, a rotatable core, bearings for positioning said rotatable core within said field structure, extended shafts at each end of said rotatable core journaled in said bearings, faces on the magnetic field structure at each end, symmetrically arranged faces on each end of the core, said faces being continuous and consisting of radial portions extending from said shafts, curved portions connected therewith, chordal portions displaced in parallel relation on opposite sides of said shafts and tangential portions extending from said shafts normal to said radial portions of such contour as to coact with the faces of the magnetic field structure to continuously reduce the reluctance of the magnetic circuit thereby causing rotary motion of the core through a predetermined limit of travel, and means for taking off power from one end or both ends of the rotatable core.

5. A magnetic actuator of compact size having an electromagnetic field structure, a field winding associated with said field structure, a rotatable armature positioned within said field structure, said armature extending through the field structure and having composite continuous faces consisting of a curved portion, a chordal portion, a radial portion and a tangential portion at each end of the armature of such contour as to coact with corresponding mating faces on the field structure in such manner as to cause continuous reduction of the magnetic reluctance of the magnetic circuit thereby producing rotary motion through a predetermined limit of travel when the field winding is energized.

6. A magnetic actuator of compact size having an electromagnetic structure, magnetic faces on each end of said electromagnetic structure, a rotatable armature having symmetrically disposed faces at each end thereof coacting with faces of the magnetic structure, the coacting faces

of the rotatable armature being integrally related and formed from one piece rotatable as a unit, a shaft protruding from one of the ends of the rotatable armature to provide means for taking off power from one of the ends of the armature through a predetermined limit of travel, the faces on said armature being respectively radial, tangential, curved relative to said shaft, and formed in planes displaced from opposite sides of said shaft and extending parallel to each other.

7. A magnetic actuator comprising in combination a magnetic frame, an electromagnetic actuating winding disposed within said frame and having an axial bore extending therethrough, an angularly shiftable armature member journaled with respect to each end of said magnetic frame and having a centrally disposed magnetic portion located within said electromagnetic actuating winding and having pairs of symmetrically arranged magnetic pole faces coacting with said magnetic frame consisting of composite radial portions, tangential portions, curved portions and parallel extending portions displaced from the axis of said angularly shiftable armature member and shaped to continuously reduce the reluctance of the magnetic circuit through said armature member as said armature is angularly shifted with respect to said magnetic frame.

8. A magnetic actuator comprising in combination a closed magnetic frame having magnetic end plates at each end thereof, sets of pole faces formed in said magnetic end plates, an electromagnetic actuating winding disposed within said frame and having a bore therethrough aligned with the sets of pole faces in said magnetic end plates, an angularly shiftable magnetic armature having cylindrical extensions on opposite ends thereof, non-magnetic end plate members secured to said magnetic end plates and providing bearings for said extensions, pairs of magnetic pole faces adjacent each end of said armature in alignment with the pole faces in said magnetic end plates, the magnetic pole faces on said armature and the pole faces in said magnetic end plates including coacting curved portions coextensive with coacting portions which extend in spaced parallel relation to each other in both said armature and magnetic end plates and being so shaped as to continuously reduce the reluctance of the magnetic circuit therethrough as said armature member is shifted with respect to said magnetic frame and means on one of said cylindrical extensions for attaching a device to be angularly shifted by said magnetic actuator.

9. A magnetic actuator comprising in combination a magnetic frame, an electromagnetic actuating winding disposed within said frame and having an axial bore extending therethrough, an angularly shiftable armature member journaled with respect to each end of said magnetic frame and having a centrally disposed magnetic portion located within said electromagnetic actuating winding and having pairs of magnetic pole faces adjacent each end of said armature member magnetically coupled with each end of said magnetic frame, the ends of said magnetic frame being formed from laminated sheets and means embracing the opposite edges of certain of said sheets for aligning said sheets relative to each other.

10. A magnetic actuator comprising in combination a closed magnetic frame having magnetic end plates at each end thereof, sets of pole faces formed in said magnetic end plates, an electromagnetic actuating winding disposed within said

frame and having a bore therethrough aligned with the sets of pole faces in said magnetic end plates, an angularly shiftable magnetic armature having cylindrical extensions on opposite ends thereof, non-magnetic end plate members secured to said magnetic end plates and providing bearings for said extensions, pairs of magnetic pole faces adjacent each end of said armature in alignment with the sets of pole faces formed in said end plates, said end plates being formed from laminated sheets, the extremities of said non-magnetic end plate members embracing the edges of said laminated sheets for maintaining said sheets in position and means on one of the cylindrical extensions for attaching a load to be angularly shifted by said magnetic actuator.

11. A magnetic actuator comprising in combination a closed magnetic frame having magnetic end plates at each end thereof, sets of pole faces formed in said magnetic end plates, an electro-magnetic actuating winding disposed within said frame and having a bore therethrough aligned with the sets of pole faces in said magnetic end plates, an angularly shiftable magnetic armature having cylindrical extensions on opposite ends thereof, non-magnetic end plate members secured to said magnetic end plates and providing bearings for said extensions, pairs of pole faces adjacent each end of said armature consisting of curved portions and coextensive portions extending in spaced parallel relation, portions extending radial and tangential with respect to the said cylindrical extensions and normal to each other in coacting alignment with the pole faces in each of said magnetic end plates and non-magnetic

inserts in each of said magnetic end plates constituting abutment stops with respect to the radially extending portions of said magnetic armature for limiting the angular movement of said armature and means on one of said cylindrical extensions for attaching a device to be angularly shifted by said magnetic actuator.

12. A magnetic actuator comprising in combination a closed magnetic frame having magnetic end plates at each end thereof, sets of pole faces formed in said magnetic end plates, an electro-magnetic actuating winding disposed within said frame and having a bore therethrough aligned with the sets of pole faces in said magnetic end plates, an angularly shiftable magnetic armature having cylindrical extensions on opposite ends thereof, non-magnetic end plate members secured to said magnetic end plates and providing bearings for said extensions, pairs of pole faces adjacent each end of said armature consisting of curved portions and coextensive portions extending in spaced parallel relation and portions extending radial and tangential with respect to the said cylindrical extensions and normal to each other in coacting alignment with the pole faces in each of said magnetic end plates, angularly shaped non-magnetic inserts on diametrically opposite sides of the central axis of said armature and constituting abutments for the radially extending portions of said magnetic armature for limiting the angular movement of said armature and means on one of said cylindrical extensions for attaching a device to be angularly shifted by said magnetic actuator.
